ATTY

UNITED STATES PATENT OFFICE.

ALPHEUS W. ALTORFER, OF PEORIA, ILLINOIS.

WASHING MACHINE.

Application filed June 18, 1924. Serial No. 720,727.

To all whom it may concern:

Be it known that ALPHEUS W. ALTORFER, a citizen of the United States of America, residing at Peoria, in the county of Peoria and State of Illinois, has invented certain new and useful Improvements in Washing Machines, of which the following is a specification.

My invention relates to washing machines.

10 The invention has special reference to operating means for a liquid container to effect agitation within the latter to the end of promoting proper washing of materials.

15 The primary object of my invention is to promote agitating action by a swinging and attendant tipping movement as distinguished from a rotary or reciprocal movement or both of the container wherein such activity is accomplished through a continuous circular activity of a connecting member with said receptacle whereby reversing action is entirely eliminated.

20 A feature of the invention includes a novel support for the receptacle adapted to hold the receptacle in an inclined or tipped position at all times and constructed to permit the inclined receptacle to swing bodily about a point located above the bottom of the receptacle.

25 30 The invention also includes means for supporting the container including a ring member coactively related to the container and the framing members and pivoted respectively to each in such angular relationship as to permit the container to be swung bodily about a vertical axis extended through the point of intersection of radial lines through the respective pivotal supports.

35 40 The invention further includes the specific means herein shown for supporting the receptacle to enable it to function as hereinbefore indicated which includes the pivoting of a ring member to the frame support and the receptacle to the ring, the said pivots being arranged at right angles relative to one another, whereby the normal resistance of the pivotal connections respectively of the receptacle and the ring will be compensated for by the capability of the 45 50 container and the ring to yield under such resistance and to tilt relatively in opposed directions under the force supplied to cause the receptacle to be tilted in a continuously varying plane.

55 The invention also includes driving means

for effecting the swinging action of the receptacle while maintained in its tilted position.

In a further aspect, this invention provides a novel method of washing clothes in 60 a more efficient and thorough manner than heretofore employed.

These and other features of the invention and the novel method referred to will appear more fully from the following detailed description when read in connection with the accompanying drawing and will be pointed out in the appended claims.

Referring to the drawings:

Fig. 1 is a side elevation of my device as 70 viewed from a given angle.

Fig. 2 is a side elevation similar to that shown in Fig. 1, showing the tub as it would appear after crank mechanism had made a quarter turn in the direction of arrow. See 75 Fig. 1.

Fig. 3 is a top plan view of the device.

Fig. 4 is a detailed view partly in section showing driving means for effecting movement of the receptacle and of details with 80 respect to gear connection thereto.

Fig. 5 is a plan view partly in section as viewed from line 5—5 of Fig. 4, and

Fig. 6 is a detailed view partly in section showing a common manner of connecting 85 a ring member with a container.

Applicant's experience through many years of manufacture of washing machines has afforded experience in the production of practically every class of washing device 90 including what are commonly known in the trade as dolly type, cylinder type, and oscillating type, and it is with a view to improving and simplifying such known types of machines that his thought has been directed and which resulted in the development of the herein exemplified new type.

Among the disadvantages in the use of the dolly type, is the matter of moving physical elements in violent contact with a practically 100 stationary mass within the container, and also the disadvantage resulting from a required reversing action which movement is attended by a violent jar in addition to the requirements of special gear means and arrangement to effect such reversing action. The same objection is applicable to the cylinder type of machine except that no physical elements, as dolly pins, are reciprocated within the container. In the oscillating 110

type a reversing action is necessary and is attended with a jar and violent precipitation of the container content which is undesirable and is attended with the necessity of special gear arrangement that is not necessary in the matter of development of the use of my present exemplified device.

In the present device a simple swinging of the receptacle in a constant direction about a line extending through the vertical axis of the driving means causes the proper agitation within the container to effect quicker and better washing than may be had in the use of the several above numerated types of machines and this through the action of the simplest type of driving mechanism as will be apparent from the disclosure herein.

Referring to the drawings, 10 are vertically disposed framing members and 11 is 20 a cross framing member which latter serves also for supporting driving mechanism for actuating the clothes container.

12 is a container for clothing adapted to be washed. This container while shown to be cylindrical may, in fact, be fashioned in any shape desired. While no interior baffles are shown or any special means provided to supplement the normal agitation developed as a result of the peculiar movement of the 30 container, nevertheless, in practice, suitable baffles may be provided or the body of the container may be fashioned as desired to effect such supplemental agitation, although this construction is not necessarily essential 35 to the successful functioning of the device.

Referring to the principal supporting means for the container, 13 is a band applied to the upper edge of the container and is preferably fixed thereto. 14 is a frame ring 40 or band designed to be fixed to the vertically disposed framing members 10, and 15 is a ring member interposed between band members 13 and 14 and relatively spaced therebetween, said ring member being pivotally supported in connection with band members 14 as at 16 (see Figs. 2 and 3) said pivots being positioned relatively to coincide with a radial line extending through the exact vertical center of the top portion of the container. The container is supported from 50 ring member 15 by means of pivot members 17 positioned relatively on a radial line extending through the exact vertical center of the upper portion of the receptacle and in exact right angled relationship to the pivotal connections of the ring member 13 to the band member 14, whereby rotary movement of an operating member, connected with the bottom portion of container and axially disposed with respect to the vertical center thereof, and eccentrically with respect to axis of the driving means, will cause the container to be swung about the axis of said driving means thereby causing the container to be progressively tilted with respect

to its support without either rotary action of the receptacle itself or reversing action thereof. From this construction, a constant change in the level plane of the liquid content of the container will be effected to cause the latter to be continuously and progressively deflected toward the center of the container, and in addition produces a wave motion about the center of the receptacle.

Referring now particularly to means for actuating the receptacle, 18 is a gear member suitably journaled upon a stub shaft as 19, connected with cross framing member 11, said shaft being provided with a hub portion 20 to which said hub member is connected. A crank arm 21 is provided with the upwardly extending boss or stud 22 exteriorly threaded as at 23 and with its upper face fashioned with a circular depression 24 adapted to receive a ball member associated with an operating member connected with a container. 25 is a drive shaft supported in cross framing member 11 adapted to be driven from any suitable 90 source of power. 26 is a gear member fixed on said shaft and adapted to mesh with gear member 18 whereby as shaft 26 is driven, gear member 18 will be turned about its axial center imparting a similar movement 95 to crank arm 21.

A spindle 27 serves as an operating member for the container and is adapted to be fixed to the bottom portion of the latter as by means of the flanged plate as shown connected with said spindle and to project some distance therefrom, said operating member being provided, as hereinbefore noted, with the ball fashioned extremity as 28, said ball member being seated in the depression in 24 of boss member 22 on crank arm 21, said members being properly related for coactive relationship by means of a perforated 105 interiorly threaded cap nut 29 through relative thread engagement between said cap nut and 110 boss member.

While the operation of the different parts and the cycle of the machine as a whole have been set forth in the foregoing description, they may be preferably summarized as follows: When the source of power is connected to the crank arm 21, the inclined tub or receptacle is given a swinging movement about a substantially fixed point located near the top of the tub at the intersection of a prolongation of the driving axis 19 and the vertical axis of the tub. The progressive tilting of the tub about this point causes a dashing wave motion of the water contents of the tub about, toward and from a point located in the vertical axis of the tub. This wave motion of the contents results from the varying positions which the tub progressively assumes whereby the water content is continuously driven or hurled to- 120 125 130

ward the central axis of the tub during the swinging movement of the latter.

What I claim is:

1. In a washing machine, a tub, means at the upper part of the tub for supporting the same for tilting movement in all directions while leaving the tub unobstructed from above, and means operable from below said supporting means for effecting the universal 10 tilting of the tub on the supporting means.

2. In a washing machine, a tub, supporting means within which the upper part of the tub is movably mounted to enable the same to tilt in all directions, and means for 15 effecting the universal tilting of the tub on said supporting means.

3. A washing machine having in combination, a support, a tub, means for suspending the tub for universal tilting movement from 20 said support, above the vertical center of said tub, the said suspending means being constructed and arranged to permit a wave motion of the tub about, toward and from a point lying approximately in the vertical 25 axis thereof, and means effecting the movement of the tub.

4. In a washing machine, a support, a tub, means wholly interposed directly laterally between adjacent portions of the body of the 30 tub and said support for supporting the tub for tilting movement in all directions within the support, and means for effecting the tilting of the tub.

5. In a washing machine, the combination 35 with a supporting frame, of a tub, movable rigid connecting means between the top portion of the tub and the supporting frame permitting the tub to tilt in every direction from a central point in the plane of the connecting means, and means operable from

below said connecting means for progressively tilting the tub.

6. In a washing machine, a wash tub, means for suspending the wash tub to permit it to be progressively tipped in all directions 45 about a relatively fixed point, comprising a gimel-ring unit from which the tub is suspended, means for supporting the gimel-ring unit, and means for tipping the tub about said point.

7. In a washing machine, a tub, means supporting the same for universal tilting movement on an axis located above the bottom of the tub, and means for effecting said 50 tilting movement comprising rotatable operating means, the axis of which intersects the axis of tilting movement of the tub, and an off-set connection between said rotatable operating means and the bottom of the tub, the axis of said off-set connecting means also intersecting the axis of tilting movement of the tub, the off-set connecting means being of a length to prevent the tub from assuming a horizontal position at any point of rotation of the rotatable operating means. 55

8. The method of washing articles which consists in depositing said articles in a body of liquid and imparting thereto a dashing wave motion from substantially all points toward, from, and about a substantially fixed 60 central top portion of said body of liquid.

9. A washing machine having in combination, a permanently tilted tub, a gimel ring for supporting the tub between the top and bottom thereof for tilting movement in 75 all directions about a substantially fixed point within the confines of the tub, and means for effecting the tilting of the tub.

In testimony whereof I affix my signature.
ALPHEUS W. ALTORFER.
